ARTHUR J. OLSEN, OF CHICAGO, ILLINOIS, ASSIGNOR TO PERMO PRODUCTS CORPORATION, OF CHICAGO, ILLINOIS, A CORPORATION OF ILLINOIS

NEEDLE

Application filed January 2, 1932. Serial No. 584,350.

The invention relates to improvements in styli or needles for sound reproducing and recording devices and particularly to a sound reproducing or recording needle having an improved alloy metal wear-resisting record-engaging portion.

An object of the invention is to provide a needle of the character referred to with an improved record-engaging portion, which is not susceptible to rust, corrosion, or misshaping during continued use.

Another object is to provide an improved needle of the character referred to having a body formed of either unalloyed metal, or metal alloy, such as steel, nickel, or copper, and a nib or point of hard material, such as for example, a hard wear-resisting alloy metal known to the trade as "Romet", including tantalum carbide and a binder of nickel, whereby material wear of the needle is practically eliminated and the volume of sound reproduced or recorded thereby remains substantially constant during continued use.

Another object is to provide an improved needle with a very hard wear-resisting record-engaging portion shaped to remain in proper adjustment and outlive the usefulness of numerous phonograph records, or the like.

Another object is to provide an improved needle of the character referred to with a "Romet" record-engaging portion ground to the requisite degree of fineness, whereby the volume and quality of sound reproduced or recorded thereby may be properly controlled.

Another object is to provide a needle of the character referred to having a "Romet" record-engaging portion formed with means to insure the necessary flexing of said needle laterally or transversely of the record groove to effect full tone reproduction.

Another object is to provide a needle with an improved record-engaging portion formed of an alloy metal, having no grain, adapted to receive a very fine finish and shaped to insure a smooth line contact with sound creating undulations forming the side walls of the groove in a record to minimize scratching and record noises and insure perfect reproduction or recording of sound.

Another object is to provide a needle of the character referred to which does not materially wear the record, even after long continuous service.

The foregoing and such other objects of the invention as will appear hereinafter as the description proceeds, will be more readily understood from a perusal of the following specification, reference being had to the accompanying drawing, in which:

Fig. 1 is an enlarged elevational view, showing one type of the improved needle associated with a record groove.

Fig. 2 is a fragmentary side elevational view of the needle, taken substantially on line 2—2 of Fig. 1.

Fig. 3 is a horizontal sectional view, taken on line 3—3 of Fig. 1.

Fig. 4 is a fragmentary view similar to Fig. 1 showing a modified form of needle.

Fig. 5 is a fragmentary elevational view of a needle having an arrow-shaped head.

Fig. 6 is a fragmentary side elevational view of the needle shown in Fig. 4.

Fig. 7 is a fragmentary elevational view of a modified form of needle.

Fig. 8 is a similar fragmentary elevational view of another form of needle.

Fig. 9 is a fragmentary perspective view of a needle formed from flat stock.

Figs. 10 and 11 are front and side elevational views, respectively, of a reproducing needle, embodying the improved record-engaging portion.

Fig. 12 is a perspective view, partly in section, of a modified form of cutting needle.

The invention resides in the provision of an improved needle for use in reproducing or recording sound from undulations forming the side walls of a groove in a record. Needles of known types usually are formed with a shank, tapered at one end to a point or edge, adapted for engaging in the groove. Such needles usually are used in connection with records having undulations forming the side walls of the groove. Needles of this character, however, wear quickly at the point until they conform to the pitch of the side walls of the groove. The continued use of such needles, so worn, results in scratching

85

90

95

100

and wearing down of the undulations, since the entire weight of the needle and sound box, because of such wearing, rests against the undulations.

5 Needles of this type and of types similar to those illustrated in the various figures of the drawing have been provided with record-engaging portions formed of various metals and alloy metals which, when properly 70 ground, serve satisfactorily for a period of time without requiring adjustment or replacement. Such metals or alloy metals heretofore used for providing a record-engaging portion on needles, lack the requisite fine texture necessary to provide a smooth highly 75 polished finish necessary to prevent scratching and wearing down of the undulations in the record groove during continuous use. The improved material has no grain and is 80 of an extremely fine texture, it being formed of granulas fused together under high pressure. When ground and polished, the improved material presents a smooth wear-resisting non-porous surface for engaging in 85 and sliding smoothly along the groove of the record without causing said record groove to wear.

Referring to the drawing in detail, one 90 form of the improved needle, shown in Figs. 30 1 to 3, inclusive, comprises a round body portion or shank 11, preferably formed of phosphorous bronze, having a record-engaging portion 12 fused or otherwise secured to one end. The record-engaging portion 12 95 preferably is formed of the improved hard wear-resisting alloy metal, known to the trade as "Ramat", including tantalum carbide with a binder of nickel. Heretofore, the record-engaging portions of needles having alloy 100 metal tips of the character heretofore referred to have been formed of iridium, osmium, or other suitable hard material, but none of these contain the necessary degree of 105 fineness in texture essential to full tone reproduction and recording. After the portion 12 is fused or otherwise secured to the shank 11, said shank preferably is swedged, as at 13, adjacent the portion 12, as illustrated 110 in Figs. 1 and 2.

50 After swedging, the record-engaging portion 12 is ground on opposed sides and around its edges to provide a record-engaging portion substantially elliptical in cross section, as 115 illustrated in Fig. 3, having a smooth end 55 providing a substantially knife-like edge 14 for riding along the bottom of the groove 15 in a record 16, whereby no appreciable weight 120 is carried by the undulations forming the side walls 17 of the groove. Concentrating 60 the weight of the needle and the sound box (not shown) upon the smooth bottom of the groove further minimizes the usual record 125 noises, such as for example, surface scratching.

65 The swedged portion 13 of the shank 11

reduces flexing and vibration of the shank in a direction longitudinally of the record groove and provides for a limited amount of flexing transversely of said groove, which often is desirable to insure reproduction of full tone quality while using sound records having undulations forming the side walls of the groove. It can readily be understood 70 that the provision of a record-engaging portion formed of "Ramat", having no grain and being of extremely fine texture, eliminates the usual record noises and maintains, because of its non-wearing qualities, a line contact with the sound creating undulations. Full tone qualities may be reproduced 75 because all undulations are readily contacted and sound is picked up or recorded without distortion.

80 Due to the long wearing qualities of the record-engaging portion 12 and the elimination of wearing friction between the needle and undulations, the improved needle outlasts thousands of records and the records remain serviceable longer than when employing needles of the known type having wear-resisting record-engaging portions formed of coarse, grained porous alloy metals of lesser degrees of hardness.

85 Fig. 4 shows a needle formed substantially like that shown in Figs. 1 to 3, inclusive. In this form the swedged portion 13a is disposed at right angles to the elliptical record-engaging portion 12 to insure flexing of the needle longitudinally of the record groove, should such flexing be requisite to perfect 90 reproduction of sound from certain types of sound records.

95 Figs. 5 and 6 illustrate another type of reproducing needle, the body portion 11a of which is formed with a substantially arrow-shaped end 18. The arrow-shaped end 18 preferably is tapered inwardly on all sides and a record-engaging portion 12a of 100 "Ramat" is brazed or welded on its end. In this instance, the hard record-engaging portion 12a also is formed with a substantially 105 knife-like edge adapted to align with the groove of a record and ride along the bottom thereof.

110 The needle shown in Fig. 7 is of the ordinary type having a round body portion or shank 11b, tapered at 19 towards one end, and having a hard wear-resisting point 12b of "Ramat", fused or otherwise secured thereon.

115 The needle illustrated in Fig. 8 is similar 120 in all respects to that shown in Fig. 7, except that a ball point record-engaging portion 12c of the improved material adapts the needle for use on records having sound creating undulations on the bottom of the record groove.

125 In the needle shown in Fig. 9, the body or shank 11d is formed of flat stock having its end tapering to a substantially knife edged record-engaging portion 12d of the improved 130 hard material.

The needle shown in Figs. 10 and 11 is formed with a substantially triangular shaped "Ramat" record-engaging portion 21. In this form of needle the body portion 22 preferably is substantially square in cross section and the record-engaging portion is tapered on its two opposed sides 23 providing a substantially knife-like edge 24. One of the remaining sides 25 of the record-engaging portion also is tapered inwardly toward the edge 24 to reduce the length of said edge and the frictional surface wearing on the record. This needle, in shape, is substantially like one form of needle used in recording sound on a record and the improved "Ramat" record-engaging portion shown may be used for such work.

A form of cutting tool is shown in Fig. 12, said tool comprising a suitable round body 20 portion 26 having an annular cutting edge 27, formed by recessing the end of a "Ramat" tip 28, fused on one end of the body portion.

Since the improved "Ramat" record-engaging portion retains its proper shape and position relative to the groove indefinitely, the improved record-engaging portion does not scratch or cause undue wearing of the record. The "Ramat" record-engaging portion is practically indestructible, having a hardness of approximately 9.2, and as it is of extremely fine non-porous texture having no grain, it provides a point that can be highly polished to reduce further wear and scratching. The wearing qualities and reproduction service of the improved needle are far superior to any heretofore obtained in sound reproduction, and it is to be understood that the shank may, if desired, be formed of any suitable metal or metal alloy, such as steel or nickel, without sacrificing the advantages obtained thereby or departing from the spirit of the invention or the scope of the appended claims.

I claim:

1. A needle having a tip of alloy metal including tantalum carbide and nickel.
2. A metallic needle having a record-engaging alloy metal tip including tantalum carbide and nickel.
3. A needle for recording or reproducing sound having, in combination, a metallic body, and a record-engaging alloy metal tip on said body including tantalum carbide and nickel.
4. A needle adapted to co-operate with a groove in a record comprising, in combination, a shank, and a record-engaging portion on said shank, said record-engaging portion being formed of alloy metal including tantalum carbide and a binder of nickel.
5. A needle for recording or reproducing sound comprising, a body, and a hard wear-resisting alloy metal tip, including tantalum carbide and a binder of nickel, fused on one end of said body.
6. A needle for recording or reproducing sound comprising, a body, and a hard wear-

resisting alloy metal tip fused on one end of said body, said tip including tantalum carbide and nickel, and being formed with a substantially knife-like edge.

7. A needle having a tip of alloy metal including tantalum carbide and a binder of nickel. 70

8. A needle for sound reproducing machines having a substantially flat record-engaging portion formed of tantalum carbide and nickel. 75

9. A needle having a record-engaging portion of tantalum carbide and nickel formed substantially elliptical in cross section.

10. A needle having a shank formed of bronze, a wear-resisting record-engaging portion on one end of said shank, consisting of tantalum carbide and nickel, and means on said bronze shank to reduce vibration therein. 80

11. A needle, for a sound reproducing machine, comprising, in combination, a round shank flattened and flared adjacent one end, and a record-engaging portion secured to said end; said record-engaging portion consisting of a hard alloy metal including tantalum carbide and nickel and being substantially elliptical in cross section and tapering towards its end to provide a substantially knife-like edge. 90

12. A needle, for sound reproducing machines, comprising, in combination, a shank, a substantially flat wide portion adjacent one end of said shank, an alloy metal record-engaging portion fused on said end, said record-engaging portion including tantalum carbide and nickel and tapering towards its end to provide a substantially knife-like edge. 95

13. A needle comprising, in combination, a shank, a record-engaging end on said shank consisting of tantalum carbide and nickel, and a portion of said shank adjacent said record-engaging end being substantially flat to allow a limited amount of flexing of said needle. 105

14. A needle formed of comparatively soft material having a wear-resisting record-engaging portion on one end formed of a hard alloy metal including tantalum carbide and nickel, and means formed in said needle to insure limited rigidity thereof. 110

15. A needle for reproducing sound comprising, in combination, a body, a portion of said body being substantially flat, said flat portion tapering on all sides toward the same end, and a record-engaging portion on said tapered end formed with a substantially knife-like edge, said record-engaging portion being formed of a hard alloy metal including tantalum carbide and nickel. 115

16. A needle for recording sound comprising, a body, and a hard alloy metal tip including tantalum carbide and a binder of nickel fused on one end of said body. 120

In testimony whereof I affix my signature
10 South LaSalle Street, Chicago, Illinois.

ARTHUR J. OLSEN. 125
